GARMENT PROTECTOR

Harold Tecumseh Meek, St. Louis, Mo.

Application March 13, 1933, Serial No. 660,547

3 Claims. (Cl. 2—53)

This invention relates to garment protectors, and more particularly to means for shielding a garment from becoming soiled by perspiration exuded from the armpits.

5 The principal purpose of the invention is the provision of an absorbent shield for this purpose which can be produced so economically that it may be wholly discarded after a day's or an evening's use and a fresh one substituted.

10 Another object is the provision of a shield which, although having sufficient strength and absorptive capacity to last at least a day, will be extremely thin and compact, thereby obviating the discomfort that inevitably accompanies bulkiness.

15 Another object is the provision of a shield that is constructed wholly of thin, loose, porous material to enhance its ventilative qualities.

Another object is to provide means for preventing the derangement or disintegration of the thin, loose material, and for rendering the shield mechanically strong without unduly complicating its structure.

20 Another object is to provide thin, flexible, inconspicuous, comfortable, simple, inobtrusive means for readily attaching or detaching the shield to the seam that connects the sleeve to the body of the garment.

25 Other objects, advantages and desirable features of the invention will appear in the course of the following description of an illustrative embodiment of the spirit of the invention.

30 In the accompanying drawing forming part of this specification, in which like numbers of reference denote like parts wherever they occur,

Figure 1 is an elevation of a garment protector embodying the features of this invention;

35 Figure 2 is a view of the same as it appears when its flaps are extended, looking toward the inner faces of the flaps;

40 Figure 3 is a sectional view on the line 3—3 in Figure 1, the thickness being exaggerated to show the details more clearly;

45 Figure 4 is a sectional view taken on the line 4—4 in Figure 1, also exaggerated;

Figure 5 is a fragmentary, exaggerated, sectional view taken on the line 5—5 in Figure 2;

50 Figure 6 is an elevation of a blank of reticulate material that forms a part of the protector; and

Figure 7 is an elevation of a blank of absorbent material that forms a part of the protector.

55 The protector comprises a pair of closed en-

velopes or hollow flaps 1, filled with suitable absorbent material, exemplified by thin sheets 2, of fluffy loosely packed cotton or cellulose fibre. The absorbent sheets 2, being easily disintegrable, are reinforced by light open fabric or 60 reticulate material, exemplified by sheets 3, of cheese cloth or surgical gauze, that expose the absorbent sheets 2. The sheets 2 and 3 are preferably in the form of approximately crescent-shaped blanks, having upper concave arcuate edges 4, that follow the general contour of the arm pits. The reticulate blanks 3 are secured to the opposite faces of the absorbent blanks 2 by any suitable means, exemplified by marginal stitching 5, which, also, serves to join 65 along the arcuate edges 4, a pair of the composite flaps 1, so formed of the blanks 2 and 3.

The shield is worn in the arm hole of a garment with one flap 1, in the sleeve and the other flap 1, inside the body of the garment. It will 70 be observed that the inner or garment side 6, of each flap, as well as the outer or arm pit side 7, of each flap, is formed of reticulate material, thereby permitting the air to circulate through all the material of the flaps and giving 75 greater comfort to the wearer. The flaps 1, are of sufficient thickness or absorptive capacity to absorb a day's or an evening's exudation of perspiration without passing it through the thickness of the protector to the garment, and yet 80 not so thick or bulky as to impair unduly its ventilative qualities or to feel uncomfortable. The stitching 5, secures the absorbent material in place in the pocket of each flap 1, preventing 85 its disturbance, displacement or disintegration.

The protector may, if desired, be attached to the body of the wearer by adhesive material, such for instance, as court plaster or surgeon's 90 tape, or it may be likewise adhesively attached 95 to the garment to hold it in place. Preferably, however, the protector is provided at its opposite ends, in juxtaposition to its seam or line of fold 8, with flexible elongated elements or straps 9, of loop formation, whose ends 10 are secured 100 by means of stitches 11, to the inner face 7, of a flap 1. The straps or ribbons 9, extend through the loops 12, of clips 13, of a well known type, whose free ends 14, may be pressed securely against the opposite sides of the seams 105 of the garment that connect the sleeves to the body thereof. The straps 9 are preferably seamed to the inner or garment side 6 of the protector so as not to irritate or chafe the arm pits of the user.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. A garment protector comprising a pair of hollow flaps formed of light open fabric and foldable on their line of juncture; fluffy, loosely integrated, absorbent sheet material in the flaps, looped straps extending from the opposite ends of the line of juncture; stitching uniting the straps, the light open fabric and the absorbent material; and clamping clips held in the loops of said straps.

2. In a garment protector comprising a pair of hollow flaps formed of light open fabric and foldable on their line of juncture, absorbent

20

sheet material in the flaps, flexible looped straps extending from the opposite ends of the line of juncture, stitching uniting the straps to the inside of the flaps, U-shaped clips held in the loops of the said straps.

3. A garment protector comprising four superimposed blanks of flexible sheet material, a sheet of absorbent material interposed between each outer and the inner blank adjacent thereto, the said blanks of flexible material being foldable on their line of juncture, flexible looped straps extending from the opposite edge of the line of juncture and stitching attaching the said flexible looped straps on the inside of the said garment protector, U-shaped clips held at right angle in the outer end of the said flexible looped straps, the said U-shaped clips having prong members to co-operate with apertures to secure the garment protector to a garment.
